UNITED STATES PATENT OFFICE.

EDWARD B. HESS, OF NEW YORK, N. Y., ASSIGNOR TO ROYAL TYPEWRITER COMPANY, INC., OF NEW YORK, N. Y., A CORPORATION OF NEW YORK.

TYPEWRITING MACHINE.

Application filed January 14, 1922. Serial No. 529,179.

To all whom it may concern:

Be it known that I, EDWARD B. HESS, a citizen of the United States, residing at Manhattan Beach, in the county of Kings, New York, and State of New York, have invented certain new and useful Improvements in Typewriting Machines, of which the following is a specification.

This invention relates to typewriting machines of the front strike, visible kind, in which the type bars are impelled to the printing point on the platen by the depression of the key levers which are connected to the heels of the type bars by flexing connections which are of such nature as to move the type bars toward the platen with accelerated velocity. Such mechanism, broadly stated, is found in all standard Royal machines, and in the machine now in use and shown in my Patent No. 1,390,708 of Sept. 13, 1921, I have illustrated an arrangement of flexing connections between the key levers and the type bars whereby the noise produced by the impact of the type bars on the platen is greatly reduced. According to my present invention, the broad features shown in such patent are embodied in a novel arrangement of the connections between the key levers and the type bars. My present invention also involves novel features of construction in which provision for reducing noise is not necessarily made, but which are useful in machines of different types. Universal bar mechanism constructed in accordance with my present invention is of an entirely new form and may be used in various kinds of machines.

In the preferred way of carrying out my present invention, the heels of the type bars are connected to relatively short key levers by links which are inclined forwardly and downwardly, their front lower ends being connected with the upper ends of vertically arranged levers which are pivotally mounted at their lower ends to move about a fixed axis below the key levers and are operatively connected with the key levers by slot and pin connections arranged in a novel way. The key levers are normally held in upper position by springs and springs are also employed to return the type bars to the normal position of rest and to hold them there. The connections between the key levers and the type bars are such that the mechanism is locked when the parts

are in normal position, it not being possible for the type bars to rise until the key levers are depressed. In this way, rebound of the type bars on their return to their rest is prevented.

In the use of such mechanism, when a key lever is depressed, the flexing connections are so operated as to bring certain parts thereof to a toggle locking or dead center position with the type bar a considerable distance from the platen, the further movement of the type bar to the platen being caused by its momentum. This toggle locking or dead center position preferably is made between the pivots of the type bars and the pivotal connections on the opposite ends of the pull links with the heels of the type bars and the upper ends of the vertical levers to which the front ends of the pull links are connected. The vertical levers are slot and pin connected with the short key levers near their rear ends, the pivots about which the vertical levers turn being located below the key levers. In this way, when a type bar is at rest, it is so locked that it cannot rebound or rise until the associated key lever is depressed. In this new way of connecting the type bars with the key levers, it will be observed the power supplied by the key levers is applied to the flexing connections between their pivotal connections with the heels of the type bars and the support about which all of the front vertical levers move.

The escapement mechanism in my new machine is similar to that found in all standard Royal machines, but the universal bar mechanism is entirely different. The universal bar proper is located in the front part of the machine above the front portions of the key levers and between them and the front ends of the type bars. This universal bar proper, which is in the form of a horizontally arranged rod, is carried by vertical arms attached to a horizontal rock shaft carrying a downwardly extending arm, link connected with a vertical lever in turn connected by a link with the escapement mechanism. The universal bar mechanism is operated by the type bars instead of by the key levers as usual, each type bar being equipped with a horizontally arranged link, the rear end of which is pivotally connected with the associated type bar near its heel, and the front end of which is formed with

a hook or loop through which the front rod of the universal bar mechanism extends. Normally the loops or hooks are out of operative connection with the universal bar rod, and are thus held by springs, but as the type bars approach the platen and arrive at the commencement of the momentum period, the hooked or looped ends of the universal bar links engage the universal bar, and thereafter the universal bar mechanism is operated to actuate the escapement.

In the accompanying drawings:-

Figure 1 shows partly in elevation and partly in section, portions of a typewriting machine embodying my improvements.

Figure 2 is a diagrammatic view showing by full lines the position of certain parts at the commencement of the momentum period, and by dot and dash lines the position of these parts at the time that the type bars impinge the platen.

Figure 3 is a developed plan view substantially on the irregular line 3--3 Fig. 1 showing the arrangement of the universal bar links indicating the differences in shape therein at the center and at the sides of the machine, the rock shaft and the links which support the front rod of the universal bar mechanism being moved from under the front ends of the links in order to more clearly illustrate the manner in which they are connected with other parts of the mechanism.

Part of a typewriting machine carriage is indicated at A, and B indicates a platen. A type bar segment is shown at C, a type bar guide at D, and escapement mechanism at E. The platen with its carriage are moved vertically for ease printing and the escapement mechanism moves vertically with the carriage. The type bars F are pivotally connected with the segment at c and normally lie horizontally as shown, their outer front ends being supported by a cushioned type bar rest G. The key levers H are comparatively short and their rear ends are pivotally mounted at h in a support I. A dust shed J is arranged over the pivots of the key levers, and springs K, attached to the dust shed and to the key levers, serve to return the levers to normal position. The upward movement of the key levers is arrested by a cushioned stop L of usual construction.

The type bars are connected to the key levers by pull links M and levers N, the latter being arranged vertically but slightly inclined from their lower ends upwardly and forwardly when in normal position. The lower ends of the levers N are pivotally mounted in a support O, all of said levers being pivoted to move about the axis of the pivot rod o which extends through the lower ends of all the levers. The upper ends of these levers are connected by the links

M with the heels of the type bars at x. Each lever N is connected to the associated key lever by sliding or slot and pin connection. The slot n in each lever is located about midway between its upper and lower ends and is inclined from its upper towards its lower end. The pin n' extends through the slot n and preferably carries a flanged roller as shown. When a key lever is depressed, the pin n' moves downwardly in the inclined slot and in so doing, moves the upper end of the lever N forward, thus pulling the link M forwardly and causing the associated type bar to move toward the platen. A full depression of the key lever causes the associated type bar to move to a position considerably in advance of the platen, the further movement of the type bar to the printing point being caused by its momentum. The position to which the type bar is moved by the depression of the associated key lever is indicated at X. At this time, the related parts occupy the position shown by dotted lines in Figure 1, and by full lines in Figure 2, where it will be observed the pivot of the type bar and the points x and y where the link M joins the type bar and the lever N are in line with each other, i. e., in a dead center or toggle locking position, but the momentum of the type bar carries it to the printing point as indicated by the dot and dash line in Figures 1 and 2. It has been demonstrated that this type of flexing connection is most serviceable in machines involving the noise reducing features of my prior invention as well as in other machines. The feature of locking the type bars when in their normal position, which involves the prevention of a rebound thereof when arriving at normal position, is an important feature of the action.

In the machine shown, the type bar segment is semi-circular and the type bars are arranged in a semi-circular series, the pivots of the type bars being at different distances from the key levers. For this reason the pull links at the ends of the machine are connected to different points on the heels of the type bars from those at which they are connected in the central portion of the machine. It will be understood also that for the reasons above stated the levers N at the ends of the machine are somewhat longer than said levers in the central portion of the machine. By thus varying the lengths of said levers and varying the points of connection of the pull links with the heels of the type bars, a uniform operation of the mechanism is effected.

The universal bar mechanism differs materially from that used in the standard Royal machine, most of the mechanism in the present instance being arranged in the front part of the machine below the type

bars, and for the most part above the key levers. The universal bar proper is in the form of a rod Q carried by vertical arms q attached to a rock shaft R from which depends an arm r connected by a link s with a vertical lever S pivotally mounted at its lower end on the support O. The upper rearwardly extending end of this lever is connected by the link T with a rocker plate 10 e' of the escapement mechanism. An arm r' projecting upwardly and rearwardly from the rock shaft R limits the return movement of the rock shaft by striking against the frame piece L.

15 The universal bar is operated by links V connected to the type bars near their rear ends and having hooked or looped ends v through which the rod Q extends. Normally the front ends of the links V are out of contact with the rod Q, but when a key lever is depressed, the associated type bar is moved toward the printing point as before described and the front end of the link v engages the rod Q and the universal bar 20 mechanism is operated through the connections before explained. This operation of the universal bar occurs at the commencement and during the momentum period of the type bars. Springs W attached at their 25 rear ends to the link V have their front ends attached to a plate W' and serve to return the type bars and parts connected therewith to normal position. In other words, these springs are employed to return 30 the type bars to normal position and to hold them in place against vibration and they, of course, also return the universal bar links V to their normal position.

By reference to Figure 3, it will be observed that the links V are so shaped as to accommodate the varying differences of the type bars in the segment, the levers at the center of the machine being straight while those on the opposite sides of the center 45 are bent and, furthermore, the connection of the front ends of the links with the type bars varies in order that the universal bar mechanism may be operated uniformly by all the keys.

50 The escapement mechanism, as before stated, is in general of usual construction, and need not be described in detail. A spring E², attached to the rocker plate e', is also attached to an arm e of the escapement 55 frame and serves not only to return the escapement rocker plate to normal position, but also the universal bar mechanism.

The mechanism shown and described 60 operates harmoniously in the operation of different parts of the machine. The type action proper is such as to reduce noise when the type bars impinge the platen, and this type action is so related with the universal bar mechanism and escapement mechanism that the escapement mechanism is

operated during the latter part of the movement of the type bars to the platen and during what is known as the "momentum period" thereof.

The cushioned rest G is supported on a vertical plate G' which has an overhanging top portion g. This plate serves as a dust guard and it is slotted at its lower end to provide a comb guide for the key levers.

I claim as my invention:

1. In a typewriting machine the combination with the key levers and the type bars of flexing connections therebetween, comprising vertical levers mounted to turn about fixed axes, links connecting the free upper ends of said vertical levers with the type bars, and sliding connections between said vertical levers and the rear portions of the key levers, the connection between each link and a type bar, and between said link and the vertical lever being moved by the full depression of a key lever to a toggle-locking or dead center position with the type bar a considerable distance from the platen when the sliding connections have reached their lower limit of movement the further movement of the type bar to the platen being caused by its momentum.

2. In a typewriting machine the combination with the key levers and the type bars of flexing connections therebetween, comprising vertical levers mounted to turn about fixed axes located below the key levers, links connecting the free upper ends of said vertical levers with the heels of the type bars, and slot and pin connections between said vertical levers and the rear portions of the key levers, the connection between each link and a type bar and between said link and said vertical lever being moved by the full depression of an associated key into a straight line with the pivot of the type bar when the key lever is fully depressed, the further movement of the type bar to the platen being caused by its momentum.

3. In a typewriting machine, the combination with the key levers, type bars, and connections therebetween, of escapement mechanism, universal bar mechanism located in the front part of the machine, a connection between the universal bar mechanism and the escapement mechanism, links extending forwardly from the rear portions of the type bars to operatively engage the universal bar mechanism only during a momentum period in the movement of the type bars to the platen, and springs extending forwardly from the links to a fixed support and acting to return the type bars to normal position.

4. In a typewriting machine, the combination with the key levers, type bars, and connections therebetween, of a universal bar mechanism comprising a rod in the front part of the machine between the key levers

and type bars, and links extending forwardly from the type bars to said rod to operatively engage the same during the excursion of the type bars to the platen.

- 5. In a typewriting machine, the combination with the key levers, type bars, and connections therebetween, of a universal bar mechanism comprising a horizontally arranged rod lying between the key levers and the type bars, links extending forwardly from said type bars and having lost motion connection with the rod, a rock shaft supporting said rod, escapement mechanism, and means connecting the rock shaft with the escapement mechanism.

- 6. In a typewriting machine the combination with the key levers and the type bars of connections between the key levers and the type bars whereby the latter are operated, escapement mechanism, and universal bar mechanism interposed between the escapement mechanism and the type bars, comprising a horizontally arranged rod,

links extending forwardly from the type bars and engaging said rod, a rock shaft on which said rod is supported, a vertical lever link-connected with said rock shaft, and a link connection between said vertical lever and the escapement mechanism.

7. In a typewriting machine the combination with the type bars and the key levers of connections therebetween, escapement mechanism and universal bar mechanism comprising a horizontally arranged rod operatively connected with the escapement mechanism, and universal bar links connecting the type bars with said rod, the universal bar links in the central portion of the machine being straight while those at the opposite sides of the center are bent from their front portions inwardly towards the middle of the machine.

In testimony whereof, I have hereunto subscribed my name.

EDWARD B. HESS.
